UNITED STATES PATENT OFFICE.

CHARLES W. LEWIS, OF PORTSMOUTH, NEW HAMPSHIRE.

COMBINED WHIP WEIGHT AND BUFFER.

Application filed July 27, 1925. Serial No. 46,439.

This invention relates to hoisting cable attachments and has particular reference to a buffer weight therefor.

An important object of the invention is to provide a buffer weight for cables of compact and durable construction which may be readily secured in position upon a cable whip.

A further object of the invention is to provide a device of the above character adapted to prevent fouling of the cable hook.

Still another object of the invention is to provide a device which will aid the descent of the unloaded cable and hook.

Other objects and advantages of this invention will become apparent as the description progresses.

In the accompanying drawing forming a part of this specification and in which like numerals are employed to designate corresponding parts throughout the same:

Figure 1 is a side elevation of my improved buffer weight,

Figure 2 is a central vertical sectional view taken through the device as shown in Figure 1,

Figure 3 is a horizontal sectional view taken on the line 3—3 of Figure 2,

Figure 4 is a similar view taken on the line 4—4 of Figure 2.

Figure 5 is a similar view taken on the line 5—5 of Figure 2, and

Figure 6 is a perspective view of a retaining member used in connection with my improved device.

In the drawing, wherein for the purpose of illustration is shown the preferred embodiment of my invention, the numeral 10 generally indicates a portion of a cable or whip carrying at its lower extremity a conventional type of cable hook 11. The cable hook is secured to the cable by means of a ring 12, the end of the cable being doubled about the ring and secured by a pair of spaced U-bolts 13 or in any suitable manner.

My invention resides more particularly in the provision of a buffer weight to be mounted at the end of the cable adjacent the cable hook so as to aid the descent of the unloaded cable and permit the same to run freely over the pulleys. The weight is so formed so as to prevent engagement of the cable hook with a second cable hook or other objects. The whip weight or buffer embodies a body 14 of elliptical shape circular in cross section, the upper portion 15 being of reduced

diameter to form an annular shoulder 16. The lower portion 17 is of substantially increased diameter, the purpose of which will become apparent as the description progresses. The central portion of the body 14 is provided with a longitudinal comparatively large bore 18 extending from the lower end to within a slight distance of the upper extremity terminating in a reduced opening 19 extending through the upper tip portion of the body. The lower extremity of the bore 18 extends entirely through the body and is provided with an annular groove 20 adjacent the lower tip of the body, this groove being somewhat greater in diameter than the bore 18.

To facilitate the assembly of the device, the body is preferably formed of two complementary half-sections provided with outwardly extending longitudinal tongues 21 engageable with suitable recesses formed in co-acting relation in the opposite portions of the sections. With particular reference to Figures 1 and 4, it will be seen that each section carries a pair of the tongues 21 in parallel arranged positions at each side of the central bore and is also provided with a pair of recesses formed adjacent the projecting tongues. This construction permits the body sections to be firmly connected by lateral movement so that the central faces will be in contact. These body sections are maintained in associated positions by means of a ring 22 preferably of metallic construction tightly inserted over the upper reduced portions of the sections and adapted to rest upon the body shoulder 16 as shown to advantage in Figure 2.

The foregoing description clearly defines the construction and manner of assembling my improved whip and buffer and I will now endeavor to indicate the manner of mounting the device upon the lower end of a cable hook to prevent material movement of the weight. As previously noted, the lower portion of the weight body 14 is provided with an annular groove 20, this groove being adapted to receive a cable engaging collar 23. This collar is of substantially circular formation durably constructed and provided with a comparatively wide slot 24. With reference to Figure 6, it is apparent that the slot 24 extends through the greater portion of the collar, the extremities of the collar adjacent its open ends being recessed to receive a mov-

able segment 25, this segment being of sufficient thickness to fit flush within the recess. One end of the segment 25 is pivotally mounted on the collar by means of a pivot pin 26, the inner edge of the segment having an arcuate slot adapted to coincide with the longitudinal slot 24 so as to engage the double end of the cable 10 therein.

To disconnect my improved whip weight and buffer from the cable hook it is necessary to elevate the ring 22 on the upper portion of the weight body 14 so that the body sections may be laterally disengaged. This will free the body from the cable but permit the collar 23 to remain in position thereon. The collar is then removed by swinging the collar segment 25 outwardly so as to permit the collar to be readily separated from the cable. In assembling the device upon the end of the cable, the collar is first mounted in position upon the doubled end of the cable between the securing bolts 13 and the weight sections mounted in position. The provision of the laterally extending tongues 21 will prevent longitudinal movement of the weight sections and the ring 22 will prevent lateral movement so that the weight may be assembled and retained firmly in position upon the cable hook.

It is apparent, from the foregoing, that a whip weight of compact construction is provided formed so as to provide a buffer to prevent fouling of the cable hook. It will be further noted that the device is designed to be very easily mounted in position on the cable and connected so as to prevent accidental displacement.

It is to be understood that the form of my invention herewith shown and described is to be taken as the preferred example of the same, and that various changes as to the shape, size and arrangement of parts may be resorted to without departing from the spirit of the invention, or the scope of the subjoined claims.

Having thus described my invention, I claim:

1. A device of the class described including an elliptical body having a longitudinal bore formed therein, means for detachably mounting the said body upon a cable hook, a cable engaging collar mounted in the lower portion of the said body, and means for detachably associating the said collar with the said cable.

2. A device of the class described including a substantially elliptical body having a longitudinal bore formed in the center thereof, the said body having a pair of comple-

mentary sections, means for retaining the said sections in associated position upon a cable, a cable engaging ring carried by the body, and means for detachably mounting the said attaching ring upon a cable.

3. A whip weight and buffer comprising, a substantially elliptical body provided with a longitudinal bore through the center thereof, the lower end of the bore extending through the bottom extremity of the body and the upper end terminating in a reduced opening, the said body being composed of a pair of sections, outwardly extending tongues formed in the intermediate portion of the sections engageable with suitable recesses, means for retaining the body sections in co-acting positions upon a cable, and a cable locking ring movably mounted in the intermediate portion of the body engageable with a cable or the like.

4. A whip weight and buffer comprising, in combination, an elliptical shaped body having a longitudinal bore formed through the center thereof, the upper end terminating in a reduced opening, the upper portion of the body being of reduced diameter to provide an intermediate shoulder, the body being formed of two complementary sections, laterally extending ears formed on the abutting edges of the sections and engageable with oppositely disposed recesses, a ring member adapted to be snugly fitted on the upper portion of the body to retain the body sections in compact position, the lower portion of the body being provided with an internal annular groove, a locking ring movable in the said groove, the said locking ring having a pivoted segment engageable with a cable hook for retaining the whip weight in position.

5. In combination with a cable whip weight having an annular groove, a circular cable engaging ring mounted in the said groove, the said ring having a transverse slot for engagement with the cable, and a pivoted locking segment mounted adjacent one end of the ring for engagement with the cable.

6. A cable whip weight comprising an elongated body formed with a longitudinal bore through its center, the said body including a pair of laterally detachable sections, a ring removably mounted in the body adapted to engage a cable, and an exterior ring adapted to be slidably fitted on the body sections to lock the same in position about a cable.

In testimony whereof I affix my signature.

CHARLES W. LEWIS.
